FIG. 1 is a perspective view of a guitar pick-up, showing my new design, in a six string embodiment;

FIG. 2 is a front elevation view thereof;

FIG. 3 is a rear elevation view thereof;

FIG. 4 is a bottom plan view thereof;

FIG. 5 is a top plan view thereof;

FIG. 6 is a right side elevation view thereof; and

FIG. 7 is a left side elevation view thereof.

FIG. 8 is a perspective view of a guitar pick-up, showing my new design, in a seven string embodiment;

FIG. 9 is a front elevation view thereof;

FIG. 10 is a rear elevation view thereof;

FIG. 11 is a bottom plan view thereof;

FIG. 12 is a top plan view thereof;

FIG. 13 is a right side elevation view thereof; and

FIG. 14 is a left side elevation view thereof.

FIG. 15 is a perspective view of a guitar pick-up, showing my new design, in an eight string embodiment;

FIG. 16 is a front elevation view thereof;

FIG. 17 is a rear elevation view thereof;

FIG. 18 is a bottom plan view thereof;

FIG. 19 is a top plan view thereof;

FIG. 20 is a right side elevation view thereof; and,

FIG. 21 is a left side elevation view thereof.

The broken lines are included for the purpose of illustrating the environmental structure and form no part of the claimed design.
